UNITED STATES PATENT OFFICE

EDGAR ROUSE SUTCLIFFE, OF LEIGH, ENGLAND

APPARATUS FOR THE DISTILLATION OF SOLID CARBONACEOUS SUBSTANCES

Application filed September 23, 1926, Serial No. 137,316, and in Great Britain September 28, 1925.

This invention relates to process and apparatus for the distillation of coal and other solid carbonaceous substance, more especially of the kind in which heaters or regenerators are used as means for heating the gas, or the gas and steam, or the steam used as the vehicle of heat internally applied for carrying out the distillation, and the invention is more especially applicable to the distillation of solid carbonaceous substances of the character of coal, shale or wood by the internal application of heat.

The invention is especially applicable for carrying out distillation under the conditions hereinafter set forth.

The invention has for an especial object to utilize steam in the distillation of carbonaceous substances such as coals and shales, or as the vehicle of heat applied in the distillation, and to utilize a relatively considerable quantity of steam under economical conditions, so as to secure an exceptionally high yield of by-products and especially of ammonium sulphate and tar, together with a substantial quantity of light oils, and a very high yield of gas.

According to the invention the heat of the gases and vapours from the retort is utilized for the production of steam for use in the distillation, or as the vehicle of heat applied in the distillation.

According to the invention moreover the gases and vapours comprising the surplus steam used in the distillation or as the vehicle of heat, are brought into intimate contact with hot water, which is thereby heated to boiling point, and steam is thereupon evaporated from the heated water for passage into the retort after first being heated as for example within a blast stove or regenerator.

The invention comprises a method involving the alternate use of retorts provided for operation in pairs or other number with corresponding heaters, blast stoves, or re-

generators, as well as constructional features involved in such a method.

The invention also comprises means for discharging the carbonized residue from the retort, and the invention generally comprises constructional features applicable to apparatus of the type indicated.

The invention comprises the features of method and apparatus hereinafter described.

The utilization of the heat of the gases and vapours from the retort for the production of steam for use in the distillation may advantageously be carried out in apparatus such as hereinafter described, or it may be carried out in apparatus such as described in the specification of the prior Patent No. 1,584,487, or it may be carried out under conditions in which the heat is applied externally to the retort in which the distillation is effected, or in which heat is partly applied externally and partly internally, or partly or entirely by the use of heated gases passed through the retort, or partly or mainly or entirely in the use of steam preheated before admission to the retort.

The invention may advantageously be carried out under moderate temperature conditions, that is to say, in which the maximum temperature applied to the charge to be distilled is about 750° C. Thus, where the steam is used as a vehicle for the heat applied in the distillation, the steam will be pre-heated to a temperature correspondingly higher than that indicated. It will however be understood that the maximum temperature in distillation is substantially under 1000° C., in order that the use of steam shall result in the decomposition of methane, and that its reaction with carbon for the production of water gas may be avoided or minimized. Thus, under these conditions a relatively high yield of hydrogen results, with a correspondingly lower proportion of carbon mon-oxide, than if the temperature

were sufficiently high to favour the water gas reaction.

If it be assumed that 100 lbs. of steam be admitted to the retort for every 100 lbs. of coal to be distilled, and if the water vapour and gases in the retort off-take be assumed to have for example a temperature of 300° to 350° F. there is theoretically more than sufficient heat available to vaporize 100 lbs. of water at the same temperature. Thus, if the gas and vapour from the retort off-take are sprayed with the water for example at 180° F. the water used may be heated for example to 210° F. and thus on the evaporation of a part of the water and consequent cooling of the remainder to about 190° F., a substantial proportion such as 50 lbs. of steam may be produced which may be compressed to the working pressure in the retort, and may be passed through the retort after first being preheated as for example, in a blast stove or regenerator. Thus steam is rendered available by the utilization of the heat of the gas and vapour produced in the distillation.

It will thus be understood that the heat of the gas and vapour produced in the distillation may be utilized in a scrubber or generally in a heat exchanger of any suitable form.

No limitation is involved to the type of scrubber or heat exchanger used nor to its construction or operation, it being understood that the heat of the gas and vapour from the retort is utilized directly for bringing to about boiling point a water liquor which is evaporated for the supply of vapour for circulation through the retort. Similarly, no limitation is involved to the type of evaporator used nor to its construction, nor to the means of maintaining reduced pressure or partial vacuum therein.

It will be understood that the vapour is advantageously passed through a heater, blast stove or regenerator before passing into the retort where it is heated to the degree necessary for carrying out the distillation under the conditions described. The retort may be provided with two such heaters, blast stoves or regenerators, which may be used alternately for suitable periods such as one-half hour. The heaters, blast stoves or regenerators may be heated by the combustion therein of gas, and the steam produced in the manner before described may be passed through the heated blast stoves or regenerators and may be projected therein with other gas or steam. Or instead one heater, blast stove or regenerator may be provided for each retort, the make of gas being discontinued in one retort during the heating period of its blast stove or regenerator.

The gas and vapour from the retort may be sprayed with tar or other liquor before

being sprayed by the water liquor which is heated for evaporation in the manner described. Similarly, a part only of the gas and vapour from the retort may be used according to the invention, and means may be provided whereby, when the make of gas from one retort of a pair is suspended during the heating of its corresponding blast stove or regenerator, the gas and vapour from the other retort of the pair may be passed through the heat exchanger, whereby one heat exchanger and evaporator may thus be used for two or more retorts.

The invention is diagrammatically illustrated in the accompanying drawings in which

Figure 1 is a diagrammatic view of the apparatus employed for utilizing the heat of the retort vapours and gases for the production of steam for use in the distillation.

Figure 2 is a diagrammatic view of the retort and connected heaters or regenerators.

Figure 3 is a view in elevation, partly in section, of a superheater, heater and retort.

Figure 4 is a view in elevation of two retorts.

In carrying the invention into effect as illustrated in Figure 1, a scrubber *a* may be provided of the spray type, which may consist of a casing that may, for example, be disposed in position between two retorts such as *b*, and that may be divided into two parts by a vertical partition *c* or be otherwise formed into two parallel compartments, the second of which may be shorter than the first and both terminate at the lower end in a contracted open part *a*¹ dipping into an open tank or tray *d* by which a liquid seal is maintained. The partition *c* extends short of the bottom so that thus the gases and vapours which enter the casing at its upper end adjacent the upper end of the respective retorts *b* may pass downwardly in one compartment and upwardly in the next as indicated by the arrows, a spray of water being provided at the upper end of each compartment for cleaning the gases and vapours and separating from them the solid particles that may remain suspended therein, and this tank or tray *d* may drain to the ammonia liquor receiving tank of the plant, which may be disposed beneath and at the rear of the retorts and of the regenerators of the plant. From the second compartment of the scrubber *a*, the gases and vapours may issue into part of the gas main *e* which is disposed or has its lower part disposed at a slight inclination from the horizontal towards the liquid outlet pipe *e*¹, and in which gas main *e* the gases and vapours may be further sprayed through a horizontally disposed pipe *f*. A special pump may be provided for the circulation of the water or liquor to the scrubber *a*.

The liquor in the tank or tray *d* is kept

separate from the liquor used for spraying the gases and vapours in the gas main *e*. The greater part of the hot water or liquor is circulated by another pump *g* and passed 5 through the pipe *f* extending at the upper part of the greater part of the length of the gas main *e* which, for the purpose, may be enlarged in diameter, and spray pipes *f*¹ may extend within the main and thus 10 through these spray pipes *f*¹ a large volume of hot water or liquor is conveyed and sprayed through the gases and vapours as they pass through the main. The hot water or liquor thus sprayed returns through the 15 lowermost part of the gas main *e* into the liquid outlet pipe *e*¹ and passes into a settling tank *h*, and thus a constant circulation of hot water or liquor is maintained through the gas main, and as this main carries 20 a large volume of steam, the steam is condensed and raises the temperature of the hot water or liquor approximately to boiling point for example 210° F. as it enters the settling tank *h*. The settling tank *h* is 25 provided in its upper part with an inverted cylinder *h*¹ substantially less in diameter than the tank *h*, and open at its lower end so that thus, as the hot water or liquor enters the tank *h*, it flows over the closed top 30 of the inverted cylinder *h*¹ and thence passes downwardly, the tar settling at the bottom of the tank *h*, while the hot water or liquor passes upwardly within and through the inverted cylinder *h*¹, and thence passes into 35 the casing of an evaporator or flash tank *i* disposed adjacent the upper end of the settling tank *h*, where the hot water or liquor may flow over a weir *i*¹ or weirs, and thence into an outlet pipe *i*² and downward to a 40 pump tank *j* which, in turn, feeds the circulating pump *g*. Over the evaporator casing or flash tank *i* a cylindrical steam receiver or anti-priming vessel *k* is provided having at its lower end a spiral or other admission passage by which any particles of 45 water that may entrained, may be deposited and drain back to the casing *i*, the object being effectively to drain the steam as it enters the receiver *k*. 50 A high pressure steam ejector *l* may be mounted upon the steam receiver *k* and is actuated by live steam, the ejector *l* maintaining suction on the steam receiver *k* and consequently on the evaporator casing or flash box *i*, whereby steam flashes off the hot water or liquor in passing through the evaporator casing. The vapour thus drawn off is passed down a pipe *l*¹ into the main connecting pipe leading to the retorts *b*. At 55 the position of connection an exhaust steam ejector may be provided which may be supplied with steam from a steam engine, and which is exhausted at a slight pressure above the atmosphere and may form an ejection 60 apparatus to assist in maintaining suction

in the pipes leading from the steam receiver *k* and evaporator *i*. The steam thus drawn off thence passes through one or other of the valves leading into one or other of the retorts of the plant according to the cycle of operation. Overflow pipes may be provided from the settling tank *h* into an overflow tank, so that if too much liquor comes over, it may flow back automatically for recirculation through the system, while overflow pipes may also be provided from the pump tank *j* by which surplus water or liquor may pass to the settling tanks of the sulphate plant.

In operation the temperature of the hot water or liquor as it passes into the pumps may be about 190° F., while on entering the gas main, the water or liquor may be about 180° F. and will become heated in the gas main to about 210° F., it being understood that steam is produced in the evaporator under the low pressure induced by the ejector which may be from 7 to 10 lbs. absolute, and the water on reaching the pump tank may cool to about 190° F. and the steam passed to the regenerator where it is heated before passage through the retort in which its heat is utilized in the distillation of the charge therein.

It will be understood that the actual temperatures may vary according to the conditions prevailing, those indicated being given by way of example.

It will be understood that drainage pipes may be provided for the tar and liquors.

Thus, according to the invention a considerable quantity of steam may be generated under economical conditions and used in the distillation, whereby exceptionally high yields of by-products and a high yield of gas of good calorific value are secured. Thus, the gas and hydrocarbon vapours leaving the retorts will carry a considerable quantity of water vapour. The temperature on leaving the retorts may be for example 350° F. In passing through the gas main the water vapour is condensed, as is also the greater part of the content of tar, and the gas and vapours leave the gas main at *x* cooled for example to about 185° F. It has been found that the use of steam as a circulating medium under the conditions indicated give exceptionally good results where the amount of steam used is 4 lbs. per lb. of coal distilled, but no limitation is involved to the amount of steam used, and the amount of steam used may be varied according to the yields required in particular cases, but in general the amount of steam used may be substantially less.

It is preferred to use a steam injector as a convenient means of creating the necessary vacuum in the evaporator and of applying pressure within the retort.

The following figures demonstrate the

utility of the process of the invention and show the quantity of steam available per 100 lbs. of coal under the assumptions named. The following data are assumed—

5	Specific heat of gas and hydrocarbon vapours at	.3
	Specific heat of water vapour at temperatures shown at	.5
	Temperature of liquor after circulation	210° Fahr.
	Temperature of liquor for circulation	188° Fahr.
10	Latent heat of water vapour at 212° Fahr.	970 B. t. u.
	Latent heat of water vapour leaving flash box at 182° Fahr.	988 B. t. u.
	Specific heat of water	1
	Temperature of gases and vapours in retort	350° Fahr.
	Temperature of gases and vapours leaving ap- paratus	185° Fahr.

The latent heat of the hydrocarbon vapours is not taken into account.

The conditions based on each 100 lbs. of coal under carbonization may be taken to be as follows:—

20	Weight of gases and hydrocarbon vapours	= 40 lbs.
	Condensable hydrocarbon vapours in apparatus	= 10 lbs.
	Steam passed to retort per 100 lbs. of coal	= 100 lbs.
	Steam recovered by apparatus	= 120 lbs.
	Steam added as exhaust steam and for operating the ejectors	= 60 lbs.
	The steam decomposed in the retort, say	= 5 lbs.
	Steam and vapor condensed and passed from apparatus as surplus liquor	= 25 lbs.
25	Vapours contained and mixed with gases leaving ap- paratus at X in proportion at temperature named about 1 vapour—1 gas	= 30 lbs.

On the basis of the above indicated data the following figures show respectively the steam quantity and heat equations and the utilization of heat absorbed in the process:—

STEAM QUANTITY EQUATION

	Entering retort	Leaving apparatus
35	Exhaust steam and ejector steam 60 lbs.	Condensed to liquid 25 lbs.
	Steam from steam recovery apparatus 120 lbs.	Contained in gases and vapour at X 30 lbs.
40		Steam decomposed in retort and counted as gas 5 lbs.
		Recovered and returned to retort 120 lbs.
		180 lbs.

HEAT EQUATION

45 Quantities of heat absorbed in the process

From sensible heat of gases and hydrocarbon vapours entering at 350 and leaving at 185	= 40 x .3 (350-185) = 1890 B. t. u.
From sensible heat of water vapour condensed in apparatus	= (180-5-30) .5 x (350-212) = 10,005 B. t. u.
From sensible heat of water vapour entering at 350 and leaving apparatus at 185° Fahr.	= 30 x .5 x (350-185) = 2475 B. t. u.
50 From latent heat of steam condensed by apparatus	= (180-5-30) x 970 = 140,650 B. t. u.

Total = 155,110 B. t. u. absorbed.

DISTRIBUTION OF HEAT ABSORBED IN THE PROCESS

55	In 120 lbs. vapour exhausted from flash box and vaporized and passed to retort	= 120 x 988
	Radiation losses	= 118,600 B. t. u. = 36,550 B. t. u.
	Total	= 155,110 B. t. u.

For passing to the retort the recovered 60 vapour at 8 lbs. absolute requires heating to 213° Fahr. corresponding to an absolute pressure of 15 lbs. per square inch, and it is demonstrable that the energy in the 60 lbs. 65 ejector steam and exhaust steam will effect the required duty.

Thus, with ample margin for radiation losses the use of 60 lbs. of steam can induce a circulation effect equal to 180 lbs. of steam.

Means may be provided for the periodic admission of milk of lime into the tray tank and at the lower end of the scrubber or heat exchanger and of the evaporator, refuse tanks may be connected for the reception of the sludge and spent lime and liquor under the control of valves, and the sludge and spent lime and liquor may be periodically discharged from the refuse tanks through valves.

It will be understood that gas and vapour admitted to the heat exchanger may be at a temperature of about 300° F. to 350° F., and that as the liquor admitted at the top of the heat exchanger will have a temperature of about 200° F., the liquor on arriving at the lower end will have acquired a temperature of about 212° F., and possibly higher depending upon the pressure and other conditions under which the apparatus is operated.

A certain part of the hot liquor will be evaporated in the evaporator as the boiling point will be reduced according to the vacuum used. The vapour produced is then passed into the retort together with the other gases that may be used and with the steam that is projected into the retort for the purpose of circulation, while the liquor accumulating in the evaporator and which has fallen somewhat in temperature due to its partial evaporation is recirculated into the heat exchanger as before described. In this way a considerable part of the heat of the gas and vapour from the retort off-take may be recovered and used for the generation of vapour for return into the retort.

In carrying the invention into effect in 105 the arrangement of the connected retorts and heaters or regenerators as illustrated in Figures 2, 3 and 4, two vertical retorts a, a (Figure 2) may be provided, together with two corresponding vertical heaters or regenerators A, and the retorts and heaters are so connected that the charge in each of the retorts in alternating periods is adapted to be internally heated by means of gas, or of gas and steam, or of steam, which is heated to the necessary temperature by being passed through the corresponding heater. In a plant comprising the elements indicated in Figure 2, one of the heaters or regenerators is heated in alternating periods 110 and during the respective heating periods the corresponding retort is cut out. Thus, if the heating period and the gas-making period are each one-half hour, one retort is subjected to heat for one-half hour and is cut 115 out from the direct application of heat for another half-hour.

Valves B may be provided in the offtake of the respective retorts, and these may be respectively closed when the respective retort 120

is to be isolated from the direct application of heat. For this purpose a butterfly type of valve is advantageously employed, and it is mounted upon a spindle adjacent the upper 5 part of the offtake outlet and in such manner that the lower edge of the valve by partial rotation of the valve is moved outwardly and upwardly in opening. Such valves are adapted for isolating the respective retorts *a, a* in such manner as, while allowing the outward passage of any gas produced in the retort cut out, under the effect of heat previously applied, will avoid drawing through the retort any products of combustion derived from the corresponding and connected heater or regenerator during the period the retort is thus isolated. It will thus be understood that during the periods in which the respective retorts are isolated 10 the heat already applied to the charges therein may be gradually transmitted from the outside inwardly of the briquettes or pieces or particles of coal undergoing distillation, and that although the direct application of heat to the charge is discontinued during those respective periods, the vaporization continues under the conditions prevailing. Thus the respective valves *B* are so provided and set that the outlet of gas 15 and vapour from the isolated retort may be permitted while avoiding the induction of the products of combustion from the corresponding and connecting heater or regenerator.

20 When two retorts *a, a* are employed for alternate operation in the manner described, and are disposed in adjacent positions as illustrated in Figure 2, the offtake pipe for the gas and vapour, as illustrated in Figure 4, may be common to the two retorts and the upper part may be conveniently formed as a hopper-shaped fitting having inclined lower walls, and at each side an outlet valve of the form described may be mounted, while at 25 the upper end of the hopper-shaped part a spraying nozzle or nozzles may be provided by which the vapour may be sprayed with water, tar or other liquid as it passes into the hopper-shaped part and downwardly through the offtake pipe.

30 The heaters or regenerators may advantageously be worked under pressure such as about from 5. to 10 inches of water, whereby under the method of regulation described 35 none of the products of distillation from the isolated retort may pass into the corresponding and connected heater or regenerator.

35 In practice, washed and stripped gas from the retorts may be used for the purpose of 40 being heated and circulated for the application of heat to the charge in the retorts. Or instead, crude gas may be used, or as an alternative that is preferred, steam may be used as the medium for the application of heat.

In operation, it will be understood that on the termination of the heating period of one of the heaters or regenerators the outlet is closed by means of a suitable valve, and that the inlet of gas for combustion therein is cut off, while the heating medium is then admitted by suitable valves.

45 According to a modification, two heaters or regenerators may be employed for each retort, and both the heaters or regenerators 50 heated in the same periods, and the heating medium passed through them in the same periods, whereby the retort is isolated or cut off from the application of heat during the heating periods of the heaters or regenerators.

55 The retorts *a, a* as illustrated in Figures 2 and 3 may be provided of a cylindrical form of large capacity and vertically disposed advantageously one beside the other, and supported upon a frame so that the lower ends of the retorts are disposed at a sufficient height above the ground for discharging shoots to be provided, the lower ends of which are conveniently disposed, whereby 60 the carbonized residue may be discharged into a conveyor or into wagons. The retort chambers or cavities may be cylindrical, but near the lower end thereof a number of ports *C* are provided at equal distances apart in 65 the same circular line to communicate with an annular flue *D* surrounding the retort at about the same level as the ports; and communication is made between this annular flue and the upper part of the corresponding 70 and adjacent heater or regenerator *A* by a short horizontal flue, through which the whole of the heating medium may pass for use in distillation in the retort, the heating medium passing into the annular flue and 75 being uniformly distributed into the retort through the ports aforesaid.

80 At the top of the retort *a* any suitable means may be provided for charging, and such means may be similar to those usually employed in charging blast furnaces and may comprise a skip or bucket and hoist such as commonly employed in such furnaces. A bucket *E* may be provided having a movable base and cover, whereby on the 85 bucket being mounted in position and upon the mouth of the retort *a*, and the cover lowered upon the bucket, the base falls for the discharge of its contents into the retort.

90 Beneath the ports *C* provided in the retort as aforesaid, it will be understood that a space or chamber *F* out of the course of the heating gases is provided in which the residue which has been degasified to the extent required may accumulate; and beneath the 95 lower end of the retort a discharging shoot *G* may be provided of the type in which the outlet end is out of alignment with the upper end adjoining the retort outlet, and in which means are provided for feeding out the resi- 100

due continuously or periodically. Having regard to the large capacity of the retort two such discharging shoots G (Figure 3) may be provided symmetrical and oppositely disposed with their outlet ends also oppositely disposed, and capable of discharging into the same wagon. For this purpose each of the charging shoots may be diverted downwardly and outwardly into a vertically disposed part, and on the outwardly curved lower wall of the outwardly diverted part of the shoot a series of star wheels H may be mounted one beside the other, on a horizontally disposed spindle, so that upon rotation of the spindle the discharging coke is fed out into the vertically disposed part of the shoot. The lower end of the vertically disposed part of each shoot is diverted inwardly and is provided with a downwardly and inwardly inclined bottom wall upon which the discharging coke falls and from which it is projected through a lateral opening in position opposite to that of the other shoot, and such lateral discharge opening may be provided with a hinging cover-plate.

The spindle on which the star wheels H of the coke discharging mechanism are mounted may be operated by means such as an externally mounted ratchet wheel and a pawl adapted to impart to the ratchet wheel a movement that may be variable in extent, whereby the rate of discharge may be varied. A swinging balance weight which may for example consist of a bar or plate hanging across the shoot and in position above the star wheels, or a number of such, mounted in position in line, may be provided for the control of the coke passing over the star wheels. It will be understood that instead of star wheels provided as hereinbefore described any equivalent adapted continuously or periodically to feed out the coke may be employed.

The lower portion of the retort below the heating zone is arranged so that steam may be blown as a cooling medium for the residue, which steam becoming heated conveys the heat up into the retort, in such way that the heat from the cooling residue contributes considerably to the heat required for carbonization.

In lieu of steam, water may be sprayed in for the same purpose.

The heaters or regenerators A may be provided as cylindrical containers or chequered refractory brickwork, and at the upper end of each a combustion chamber may be provided surmounted by a curved dome in which a series of burner nozzles I may be provided through which, in the heating periods, a mixture of gas and air may be passed by which the heater or regenerator may become heated to the degree required for imparting its heat to the heating fluid in the succeed-

ing period, for circulation through the charge in the adjacent retort.

At the upper end of each heater or regenerator A an oil burner or burners may be provided for the purpose of applying heat at starting; but in normal running, gas generated in the plant may be used.

Exhaust steam from an engine may be utilized as the heating medium in the plant, and this may be supplemented by the heat recovered from the gas and vapour leaving the retort, as hereinbefore described.

As an alternate means for the production of steam for circulation through a blast stove regenerator or heater, water may be sprayed into a second blast stove regenerator or heater heated by the waste products from the first heater, in such way as to produce steam for passing through the heater either as the sole means for heat conveyance or as supplementary to other sources of gas or steam.

A superheater J or superheaters may be provided in the outlet flue or in the outlet flues of the heaters or regenerators, through which superheater or superheaters the hot waste gases may pass in the respective alternate periods, and the steam superheated therein may be used for direct admission to the respective retorts through the annular flue D or otherwise.

It will be understood that the respective parts of the plant are insulated to avoid radiation losses.

I claim:

Apparatus for the distillation of a solid carbonizable substance comprising in combination a retort, a scrubber, a gas main, the said gas main being adapted for use as a scrubber, an evaporator separate from the said scrubber, a superheater, and means for their connection in series, the said means being adapted for the admission into the retort of superheated steam from the superheater, for the admission into the scrubber of a mixture of gas, vapour and steam from the retort for admission into the main of gas from the scrubber, for the admission into the evaporator of hot water from the main, and for the re-circulation of part of the hot water back from the evaporator to the main, and for the admission into the superheater of the steam from the evaporator, substantially as hereinbefore described.
